(57) **CLAIM**

The ornamental design for a vertical shaft impact crusher rotor, as shown and described.

DESCRIPTION

FIG. 1 is a perspective view of a vertical shaft impact crusher rotor showing our new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a plan view thereof;

FIG. 7 is a bottom view thereof; and,

FIG. 8 is a sectional view along the section FIG. 8-FIG. 8 of FIG. 3.

The broken lines shown in the drawings illustrate portions of the vertical shaft impact crusher rotor that form no part of the claimed design.
